United States Patent Office.

WILLIAM SAGE, OF INDIANAPOLIS, INDIANA.

Design No. 3,773, dated November 30, 1869.

DESIGN FOR A MITRE-MOULD.

The Schedule referred to in these Letters Patent and making part of the same.

To all whom it may concern:

Be it known that I, WILLIAM SAGE, of Indianapolis, in the county of Marion, and State of Indiana, have invented a new and valuable Improvement in Mitre-Moulds; and I do hereby declare that the following is a full, clear, and exact description of the construction and operation of the same, reference being had to the annexed drawings, making a part of this specification, and to the letters and figures of reference marked thereon.

Figure 1, of the drawings, is an end view of my invention.

Figure 2 is a side view of same.

Figure 3 is a top view of same.

The nature of my design is fully represented in the above drawings, in which—

The letter A designates the shoe.

B B, the handles.

C, the mould-board.

D, the support or stay.

E, the brace.

F, the forming-edge.

The instrument is used for moulding plaster cornices, and is adapted to the formation of the salient and re-entering angles thereof.

What I claim as my invention, and desire to secure by Letters Patent, is—

The design for a mitre-mould for plaster or cement cornices, as shown and described.

In testimony that I claim the above, I have hereunto subscribed my name, in the presence of two witnesses.

WILLIAM SAGE.

Witnesses:
